JAR

David J. Black, Brooklyn, N.Y., assignor to Afico S.A.,
Lausanne, Switzerland, a corporation of Switzerland

Filed Nov. 7, 1961, Ser. No. 67,408

Term of patent 14 years

(Cl. D58—25)

FIG. 1 is a side elevational view of a jar, showing my new design, wherein the lower bulged portion is characterized by ribs;

FIG. 2 is a top plan view thereof;

FIG. 3 is a sectional view thereof taken on lines 3—3 of FIG. 1; and

FIG. 4 is a side elevational view of a jar showing my new design; wherein the lower bulged portion is plain.

The portions shown in broken lines are for illustrative purposes only.

The essential common feature of the two species of the design is the provision of a lower bulged portion of about the same height as the cylindrical intermediate portion of the jar, and of considerably greater height than the upper bulged portion.

I claim:

The ornamental design for a jar, substantially as shown and described.
